TRAFFIC SIGNAL CONTROLLER

Anton Diebold, New York, N. Y., assignor to The Marbelite Company, Inc., New York, N. Y., a corporation of New York

Application May 13, 1948, Serial No. 26,814

10 Claims. (Cl. 177—337)

1

The present invention relates to improvements in traffic signal controllers and relates more particularly to a traffic signal controller for automatically operating traffic signals in a predetermined timed sequence.

An object of the present invention is to provide a traffic signal controller that is capable of being used in controlling cycles of operations that involve different numbers of steps or intervals. Another object of the invention is to provide a traffic signal controller in which certain parts of the controller are standardized which results in economies in the manufacture and servicing of such controllers. Various other objects and advantages of the present invention will be apparent and best understood from the following description and the accompanying drawings in which:

Fig. 1 is a front view of a traffic signal controller embodying the invention;

Fig. 2 is a rear view of the traffic signal controller illustrated in Fig. 1;

Fig. 3 is a side view of the traffic signal controller illustrated in Fig. 1 with certain parts broken away for clarity;

Fig. 4 is a rear view showing details of the timing mechanism for the traffic signal controller illustrated in Fig. 1;

Fig. 5 is a top view of the timing mechanism illustrated in Fig. 4;

Fig. 6 is an end view of the driving mechanism illustrated in Figs. 4 and 5;

Fig. 7 is a schematic wiring diagram illustrating the electrical connections for certain parts of a traffic signal controller embodying the invention;

Fig. 8 is a front view of a dial for the traffic signal controller;

Fig. 9 is a side view of an actuating key for use in the dial illustrated in Fig. 8;

Fig. 10 is a section view taken along the line 10—10 of Fig. 2;

Fig. 11 is a side view of a switch member and contact assembly;

Fig. 11a is a plan view of the switch member illustrated in Fig. 11; and

Fig. 12 is a schematic wiring diagram illustrating an electrical circuit for a traffic signal controller embodying the invention.

As shown in Fig. 1, there is a front panel 1 having an opening therein to accommodate a dial 2. A rim 3 supporting a pane of glass is hinged to the panel 1 and encloses the opening in the panel 1 and the front of the dial 2. The dial 2, as shown in Figs. 5 and 6 consists of two

spaced plates 2a and 2b, each of which is provided with concentric rows of radial slots 4 and 5. The radial slots 4 and 5 in the respective plates 2a and 2b are aligned to receive a contact-actuating key 6 or 7 therein.

The contact-actuating keys 6 and 7 are short and long keys, respectively, and each key has a shank portion with a notch 8 formed at the base thereof in one edge of the key and a spring finger 9 positioned on the opposite edge of the key. When the keys 6 or 7 are inserted in the slots 4 or 5, the notch 8 is held in engagement with the plate 2a at one end of the slot 4 or 5 by the spring finger 9 pressing against the plate 2a at the opposite end of the slot 4 or 5. This holds the keys 6 and 7 firmly in place in the dial 2, but permits the keys to be readily removed from the dial 2 by forcing the key toward the center of the dial against the pressure of the spring finger 9 so as to disengage the notch 8 from the plate 2a. Such an arrangement allows the position of the keys 6 and 7 on the dial to be easily changed and eliminates the necessity of removing parts of the dial.

25 The dial 2 is secured to a shaft 10 that is rotatably mounted in a sleeve 11. The sleeve 11 is supported on a plate 12 that is secured to posts 13 extending from the rear of the panel 1. A gear 14 is removably secured to the end of the shaft 10 by a nut 15 so that the gear 14 can be readily changed to a gear of a different size when desired. The gear 14 is normally in driving engagement with a gear 16 that is carried on a pivoted plate 17. The plate 17 is pivoted on the plate 12 by a shaft 24 that is rotatably supported thereon. The pivoted plate 17 has an arcuate slot 18 therein through which the shaft 10 projects so that the pivoted plate 17 may be moved arcuately to disengage the gear 16 carried thereon 40 from the gear 14 when it is desired to replace the gear 14 with a different size gear. Thus, the gear 14 may be easily changed when it is desired to change the speed of rotation for the dial 2.

The free end of the pivoted plate 17 may serve 45 as a pointer in cooperation with a scale 19 carried on the plate 12 that indicates the time for a complete revolution of the dial 2. A second pointer 20 for indicating the time for a revolution of the dial 2 projects through an arcuate opening 50 21 in the panel 1 beneath the dial 2 and registers with a scale 22 located on the front of the panel. The pointer 20 is carried by a bell crank lever 23 that is pivotally supported on the plate 12 by the sleeve 11. A pin 17a carried by the plate 17 extends through an arcuate slot in the plate 12

and engages with the end of the bell crank 23 to move it and the pointer 20 when the position of the plate 17 is changed.

The shaft 24 about which the plate 17 pivots carries an intermediate gear 25 that is engaged with the gear 16 carried on the pivoted plate 17. The gear 16 remains in engagement with the gear 25 as the plate 17 is moved. A driving gear 26 is secured to the drive shaft of a permanent magnet type of synchronous electric motor 27 which is non-coasting and eliminates the use of braking circuits or the like. The driving gear 26 engages with the gear 25 to drive the dial 2 through the gearing just described. The motor 27 is removably secured to the plate 12 so that it may be replaced if necessary at any time.

Micro-switches 29 and 30 are mounted on the rear of the panel 1 above the dial 2 and have movable contact members 31 and 32, respectively, associated therewith. The micro-switches 29 and 30 are connected in electrical circuits that cause the advance of a signal controlling mechanism and also insure proper coordination between the operation of the dial 2 and the signal controlling mechanism as will be described later. The switches 29 and 30 are mounted on the rear of the panel 1 with their respective movable contact members 31 and 32 in staggered relation to each other so that the ends of the short contact-actuating keys 6 will raise the movable contact member 31 of switch 29, but do not strike the movable contact member 32 of the switch 30 as the dial 2 is rotated. The long contact-actuating key 7 has a cut out portion 7a that permits it to pass under without striking the contact member 31 of the switch 29, and the end of the key 7 raises the movable contact member 32 of switch 30 as the dial 2 is rotated.

Additional micro-switches may be mounted in line with the micro-switches 29 and 30 if they are required as when a master control system is used and such micro-switches may be operated by various length keys carried in the slots 5 of the dial 2.

The operation of micro-switch 29 by the contact-actuating keys 6 momentarily closes a circuit that will be described more fully later, connecting a solenoid 33 to a source of electrical energy S. The solenoid 33, which may be of the type shown in Patent No. 2,304,553, dated December 8, 1942, is loosely mounted in a vertical position on the rear of the panel 1 by a cross pin 34. When the solenoid 33 is energized momentarily as by the closing of the micro-switch contacts, its plunger 35 is raised to its upward position and when the contacts of the micro-switch 29 or 30 open, the plunger 35 is permitted to fall by gravity. The end of the plunger 35 of the solenoid 33 is connected to a weighted arm 36 which is raised and lowered with the plunger 35. The arm 36 is pivoted on one of the supporting brackets 37 located at right angles to the rear face of the panel 1 at the ends thereof. The arm 36 carries a pawl 38 and a stop 39 that engage with a toothed ratchet wheel 40. The toothed ratchet wheel 40 is secured to a cam shaft 41 that is rotatably supported at its ends in the brackets 37.

The stop 39 engages with the top of the ratchet wheel to hold the ratchet wheel 40 and to limit the distance that the pawl 38 can move the ratchet wheel 40 and cam shaft 41 for each operation of the solenoid 33. The stop 39 may be designed so that different movements of the ratchet wheel 40 in response to operation of the solenoid 33 may be obtained by reversing the

position of the stop 39 on the arm 36. Thus, if the ratchet wheel 40 is provided with eighteen teeth, as illustrated, the adjustable stop 39 may be positioned so that the ratchet wheel 40 will be advanced a distance corresponding to one tooth for each operation of the solenoid 33 or in eighteen steps for a complete revolution of the ratchet wheel 40, or the stop 39 may be reversed so that the ratchet wheel 40 will be advanced a distance corresponding to two teeth for each operation of the solenoid 33 or in nine steps for a complete revolution.

In a traffic signal controller embodying the present invention, the ratchet wheel 40 is provided with a number of teeth corresponding to the greatest possible number of periods or signal intervals that may be required under any ordinary conditions. If fewer signal intervals are required in a particular installation, a number of signal operating cycles may be accomplished in a complete revolution of the cam shaft 41 and under such conditions, there will be less wear and tear on the cam shaft 41.

The cam shaft 41 carries a series of switch-operating cams 42a to 42i, inclusive, that will be referred to generally as switch-operating cams 42. The cam carrying portion of the shaft 41 is square with one corner beveled to serve as guide in assembling the cams 42 on the shaft 41 in a predetermined relation. The switch-operating cams 42 may be made of a frangible insulating material in the form of a circular disc with a series of wedge-shaped segments 43 corresponding in number to the teeth on the ratchet wheel 40 spaced around the outer circumference thereof, as shown in Fig. 10.

The wedge-shaped segments 43 may be numbered and selected segments may be broken out, either before or after assembly of the cams on the cam shaft. A hub 44 is provided on each of the switch-operating cams 42 and extends axially from one face of the cam so as to position an adjacent cam in properly spaced relation when the cams are assembled on the shaft 41.

The switch-operating cams 42a to 42i, when assembled on the cam shaft 41, respectively, support the ends of a series of switch members 45a to 45i, inclusive, referred to generally as switch members 45. The switch members 45 are removably supported on terminals 46a to 46i, inclusive, referred to generally as terminals 46. The terminals 46 are carried on a bar of insulating material 47 that is supported by the brackets 37. The switch members 45 are held in contact with the terminals 46 and in engagement with the cams 42 by springs 48 carried on a post 48a extending from the terminals 46. The ends of the switch members 45 are bifurcated and have legs 49 that may be slid beneath the end of the spring 48 on either side of the post 48a in contacting engagement with the terminal 46.

When the end of one of the switch members 45 registers with a portion of a switch-operating cam 42 where one of the segments 43 has been broken out, the spring 48 urges the switch member 45 to the position illustrated in Fig. 11. When the switch member 45 is in this position, a contact button 50 carried thereon contacts with a contact button 51 carried on a second terminal 52 to close an electrical circuit that will be described hereinafter. A series of the terminals 52 indicated by reference numerals 52a to 52i are carried on a second bar of insulating material 53 that is also supported by the brackets 37.

As shown in Fig. 2, a flasher mechanism 61 is

associated with the timing motor 27 and consists of a toothed wheel 54 that is secured to the shaft 24 which is driven by the timing motor 27. The toothed wheel 54 engages with the end of a resilient contact-carrying member 55 that carries a contact 56. The contact 56 is in opposed relation to a contact 57 on a fixed contact-carrying member 58. The contact-carrying members 55 and 58 are supported in a block of insulating material 59 that is secured to an extension 60 of the plate 12 and the contact-carrying members 55 and 58 are provided, respectively, with wiring terminals 55a and 58a. When the toothed wheel 54 is rotated by the timing motor 27 the contacts 56 and 57 are opened and closed by the flexible contact-carrying member 55 riding over the toothed portions of the wheel 54.

The electrical circuits controlled by the first three switch-operating cams 42a, 42b and 42c on the cam shaft 41 and their respective switch members 45a, 45b and 45c, are shown in Fig. 7. These circuits control the operation of the solenoid 33 and movement of the cam shaft 41 in response thereto. The remainder of the switch-operating cams 42d to 42i with their respective switch members 45d to 45i in cooperation with the terminals 52d to 52i control the operation or display of the traffic signals or lights.

For the purposes of illustration, a traffic signal system having four periods or intervals of operation has been described. In such a system, there is a traffic signal having green, amber and red signals or lights, indicated by reference characters G₁, A₁ and R₁, respectively, for the main street and green, amber and red signals, indicated by the reference characters G₂, A₂ and R₂, respectively, for the cross street. The operation of the traffic signal in a four interval system requires four movements or steps of the cam shaft 41 and the switch-operating cams 42 carried thereon and the switch-operating cams 42 are designed so that during the first interval, the signal G₁ (green) for the main street and the signal R₂ (red) for the cross street are displayed; during the second interval, the signal A₁ (amber) for the main street and the signal R₂ (red) for the cross street are displayed; during the third intervals, the signal R₁ (red) for the main street and the signal G₂ (green) for the cross street are displayed; and during the fourth interval, the signal R₁ (red) for the main street and the signal A₂ (amber) for the cross street are displayed. The display of the traffic signals G₁, A₁, R₁, G₂, A₂ and R₂ in the desired sequence is controlled by the switch-operating cams 42d to 42i, respectively, by breaking out appropriate segments 43 of the switch-operating cams 42d to 42i so that the switch members 45d to 45i, which control the circuits connecting the traffic signals to the source of electrical energy S as shown in Fig. 12, are opened and closed at the proper time as the cam shaft 41 is rotated.

Referring now to the electrical circuits for the controller illustrated in Fig. 7, the movable contacts 31 and 32 of the micro-switches 29 and 30 are connected to one side of the solenoid 33 and the other side of the solenoid 33 is connected to the common or ground side C of the source of electrical energy S. The fixed contacts 29' and 30' of the micro-switches 29 and 30, respectively, are connected to the power side P of the source of electrical energy S through the switch members 45a and 45b, respectively in cooperation with the terminals 52a and 52b. In addition, the solenoid 33 is connected to power side

P of the source of electrical energy S through the switch member 45c in cooperation with the terminal 52c and the flasher mechanism 61. The cams 42a and 42b controlling the switch members 45a and 45b are arranged so that each time the key 6 closes the contacts 31 and 29' of the micro-switch 29 and each time the key 7 closes the contacts 32 and 30' of the micro-switch 30, the solenoid 33 will be momentarily connected to the source of electrical energy S and in response thereto will be operated to move the cam shaft 41 one step.

However, if the cam shaft 41 and the timing dial 2 are not operating in proper coordination for the desired signal sequence, as may happen when the controller has been operated manually without regard to the position of the dial, a point is reached where the cam 42a holds the switch member 45a open so that the operation of the micro-switch 29 by the keys 6 does not close the circuit connecting solenoid 33 to the source of electrical energy S. The cams 42a and 42b are arranged so that whenever the switch member 45a is open the switch member 45b will be closed and, thus, the condition where the keys 6 do not close the circuit to the solenoid 33 will continue until the key 7 closes the contacts of the micro-switch 30 to complete a circuit connecting the solenoid 33 to the source of electrical energy S which causes the solenoid 33 to move the cam shaft 41 one step. This movement of the cam shaft 41 permits the switch member 45a to close and thereafter the cam shaft 41 will operate in response to the keys 6 or 7 closing the contacts of either the micro-switches 29 or 30.

The position of the cam shaft 41 at which the switch member 45a is held open may be coordinated with the cams 45d to 45i controlling the traffic signals so that the period during which the controller is in this position will occur when the signals G₁ (green) for the main street and R₂ (red) for the cross street are displayed so that any delay will not affect the main flow of traffic.

When the traffic signals are operated in four interval system, as in the example described, four cycles or a total of sixteen intervals may be accomplished during each revolution of the cam shaft 41. In such case, the cam shaft 41 is automatically advanced two additional steps required for a complete revolution on the basis of the eighteen toothed ratchet wheel 40. This is accomplished by permitting the switch member 45c to close during two steps of the cam shaft 41. When the switch member 45c is closed in relation to its terminal 52c, the solenoid 33 will be momentarily connected to the source of electrical energy S by the operation of the flasher mechanism 61. The other cams 42 on the cam shaft 41 are designed so that this movement of the cam shaft 41 does not affect the circuits controlled by them.

By this arrangement the cam shaft may be moved any additional steps that may be required, depending upon the number of intervals used. For example, if seven or twelve intervals are required, the cam shaft may be moved in this manner for the four or six additional steps, respectively, that would be required for a complete revolution of the cam shaft 41. These extra or blind steps may be taken up at any desired point in the operating cycle of the controller. If the number of intervals required is clearly divisible into the eighteen step movement

of the cam shaft 41 such as three, six or nine intervals, no additional steps will need to be taken up in this manner.

The arrangement that has been described permits any change or alteration of the cycle to be made in the field by the use of a universal or standardized mechanism that is capable of being used for as many signal display intervals as may be required and does not necessitate any changes in the solenoid or other parts of the mechanism when different numbers of intervals are required. The number of intervals required is provided for by breaking out the proper segments on the cams 42 and for this reason, the controller can be readily changed at any time to a different system or number of intervals by the installation of a new set of cams only. In previous controllers of this type, it has been necessary to provide a number of different ratchet wheels with an appropriate length of solenoid plunger for each ratchet wheel in constructing controllers for a number of intervals. In such a controller when it is desired to change the number of intervals after the controller was assembled, the solenoid plunger and operating parts associated therewith had to be changed accordingly. This also made it necessary for repair and maintenance men to carry a variety of size of the same parts to repair such controllers.

A switch 62 in a circuit connecting the timing motor 27 to the source of electrical energy S may be located on the front of the panel 1 to permit the timing motor to be started or stopped as desired. A double throw switch 63 in one closed position connects the solenoid 33 in circuit with the source of electrical energy S through the micro-switches 29 and 30 for automatic operation and in the other closed position connects the solenoid 33 to the source of electrical energy S through a manually operable push button type of switch 64 for manual operation. The switch 63 for controlling the automatic for manual operation may also be located on the front of the panel 1 for convenience.

When the switch 63 is in manual position, the solenoid 33 is connected to the source of electrical energy S each time the push button switch 64 is closed. The solenoid 33 in response thereto moves the cam shaft 41 one step causing the signal display to be changed. However, when the controller is operated by manual control switch 64, the circuit through the switch member 45c and the flasher mechanism 61 continues to operate as usual and automatically advances the cam shaft 41, in the manner previously described, for such steps of the cam shaft 41 as there may be during its revolution where no change of the signal display takes place; i. e. the additional steps for a complete revolution of the cam shaft 41 referred to above. Thus, each operation of the push button switch 64 causes a change in the signal display.

In addition to the control switches 62 and 63, a four pole, triple throw switch 65 is provided and may be located on a separate panel board 66. One position of the switch 65 connects the controller to the source of electrical energy S so that it may be operated automatically or manually in the manner described above. In the second or "off" position of the switch 65, the controller is disconnected from the source of electrical energy S and in the third or "flash" position of the switch 65, the amber signals A₁ and A₂ only are connected to the source of electrical energy S

through the flasher mechanism 61 so that these signals will be displayed intermittently.

A switch 67 may be provided in the circuit with the terminals 52d to 52i connecting the traffic signals to the source of electrical energy S and the switch 67 may also be located on the front of the panel 1. A removable cover 68 may also be provided to enclose the sides and top of the controller.

10 It will be understood that those skilled in the art may make various modifications and changes in the controller that has been illustrated as embodying the present invention without departing from the scope of the invention as defined in the 15 claims appended hereto.

I claim:

1. In a traffic signal controller of the type having a rotary switching mechanism for controlling the display of traffic signals at an intersection in 20 a predetermined sequence with an electrically operated driving means for advancing said rotary switching mechanism in step by step movements in response to the actuation by a timing dial of switches connecting the electrically operated driving means to a source of electrical energy, the combination comprising a switching mechanism operable by the electrically operated driving mechanism and a flasher mechanism operated independently of said driving mechanism, said switching mechanism and said flasher mechanism being in a circuit connecting the driving means to a source of electrical energy whereby said driving means is intermittently operated by said flasher mechanism when said switching mechanism is closed.

2. In a traffic signal controller of the type described, the combination of a rotary switch mechanism controlling circuits for operating a display of traffic signals in a predetermined sequence, said rotary switch mechanism maintaining an existing traffic signal display at a number of consecutive positions thereof, a solenoid for driving said rotary switch mechanism in step by step movement in controlling said circuits, a pair of switches in parallel circuits connecting said solenoid to a source of electrical energy, a motor driven timing dial associated with said switches for operating said switches at timed intervals thereby causing said solenoid to operate and advance the rotary switch mechanism, a switching device in circuit with one of said switches, a second switching device in circuit with the other of said switches, both of said switching devices being driven by the solenoid in conjunction with the 55 rotary switch mechanism and being arranged to open the circuit to one switch when the circuit to the other switch is closed whereby the rotary switch mechanism will be advanced one step upon the actuation of either switch by the timing dial 60 when the dial is rotating in properly coordinated relation to said switching devices, a third switching device driven by said solenoid and a circuit making and breaking mechanism, said third switching device and said circuit making and breaking device being in a circuit connecting said solenoid to the source of electrical energy, said third switching device being arranged to close said last-mentioned circuit and thereby automatically render the circuit making and breaking device operative, said circuit making and breaking device being operable in a single revolution of the timing dial to advance the rotary switch mechanism a number of steps upon the completion of an even multiple of the revolutions of the timing dial and at a time when rotary switch

mechanism maintains the existing traffic signal display in a number of consecutive positions thereof, said last-mentioned number of steps plus the number of steps of the rotary switch mechanism actuated by the timing dial being equal to the number of steps required for a complete revolution of the rotary switch mechanism.

3. In a traffic signal controller of the type described, the combination of a rotary switch mechanism controlling circuits for operating a display of traffic signals in a predetermined sequence, said rotary switch mechanism maintaining an existing traffic signal display at a number of consecutive positions thereof, a solenoid for driving said rotary switch mechanism in step by step movement in controlling said circuits, a pair of switches in parallel circuits connecting said solenoid to a source of electrical energy, a motor driven timing dial associated with said switches for operating said switches at timed intervals thereby causing said solenoid to operate and advance the rotary switch mechanism, a switching device in circuit with one of said switches, a second switching device in circuit with the other of said switches, both of said switching devices being driven by the solenoid in conjunction with the rotary switch mechanism and being arranged to open the circuit to one switch when the circuit to the other switch is closed whereby the rotary switch mechanism will be advanced one step upon the actuation of either switch by the timing dial when the dial is rotating in properly coordinated relation to said switching devices, a third switching device driven by said solenoid, a circuit making and breaking mechanism, said third switching device and said circuit making and breaking device being in a circuit connecting said solenoid to the source of electrical energy, said third switching device being arranged to close said last-mentioned circuit and thereby automatically render the circuit making and breaking device operative, said circuit making and breaking device being operable in a single revolution of the timing dial to advance the rotary switch mechanism a number of steps upon the completion of an even multiple of the revolutions of the timing dial and at a time when the rotary switch mechanism maintains the existing traffic signal display in a number of consecutive positions thereof, said last-mentioned number of steps plus the number of steps of the rotary switch mechanism actuated by the timing dial being equal to the number of steps required for one complete revolution of the rotary switch mechanism, a manually operable push button switch in a circuit connecting said solenoid to the source of electrical energy and a switch for selectively connecting said solenoid to said push button switch and to the dial operated switches.

4. In a traffic signal controller of the type described wherein a display of traffic signals is controlled by a rotary switching mechanism, the combination of a rotatable shaft supporting said rotary switching mechanism, electrically operated means connected to the shaft for rotating the shaft in step by step movements, the number of said movements required for a complete revolution of said shaft being in excess of the number of said movements required for at least one complete cycle of traffic signal displays, a circuit controlled by a constantly rotating timing dial for operating the shaft rotating means and a second circuit for operating said shaft rotating means, said second circuit including a switch operable by rotation of the shaft and a switch

operable by rotation of the timing dial, said last-mentioned switch being operated a number of times during a single revolution of the timing dial, the number of switch operations being at least equal to the number of movements of the shaft in excess of the number of movements required for a complete revolution thereof.

5. In a traffic signal controller of the type described, the combination as defined in claim 4 wherein the electrically operated means for rotating the shaft includes a ratchet wheel secured to the shaft and a solenoid, the solenoid having a plunger engaging with a tooth on the ratchet wheel and advancing the ratchet wheel and shaft one step upon each energization of the solenoid.

6. In a traffic signal controller of the type described, the combination as defined in claim 4 wherein the electrically operated means for rotating the shaft includes a ratchet wheel secured to the shaft, said ratchet wheel having at least eighteen teeth thereon and a solenoid, the solenoid having a plunger engaging with a tooth on the ratchet wheel and advancing the ratchet wheel and shaft one step upon each energization of the solenoid.

7. In a traffic signal controller of the type described, the combination as defined in claim 4 wherein the last-mentioned switch controlled by the timing dial consists of a flasher mechanism connected to and driven with the timing dial.

8. In a traffic signal controller of the type described, the combination including a rotary switching mechanism for controlling a display of traffic signals in a predetermined sequence, said rotary switching mechanism controlling a plurality of cycles of the sequential traffic signal displays during each revolution thereof, a motor driven timing dial for causing step by step movement of the rotary switching mechanism at selected intervals of time with a complete cycle of traffic signal displays being accomplished in a single revolution of said dial and a second rotary switching mechanism operable by said timing dial in the operation of the first rotary switching mechanism and means for causing the step by step movements of both of the rotary switching mechanisms for the steps required to complete one revolution of the first-mentioned rotary switching mechanism in addition to the step by step movements thereof required for the number of complete traffic signal display cycles during each revolution of the first-named rotary switching mechanism, said means including an intermittently operated circuit making and breaking mechanism operable by rotation of the motor operated timing dial, said circuit making and breaking mechanism being in a circuit controlled by said second rotary switching mechanism.

9. In a traffic signal controller of the type described, the combination including a rotary switching mechanism for controlling a traffic signal display in a predetermined sequence, said rotary switching mechanism being capable of operating the sequential traffic signal display in a plurality of cycles during each revolution thereof of said switching mechanism, means including a continuously rotating motor driven timing dial for causing step by step movement of the rotary switching mechanism at selected intervals of time with a complete sequence of traffic signal displays being accomplished in a single revolution of said dial, a second rotary switching mechanism connected to and driven with the first ro-

5
tary switching mechanism, said second switching mechanism being rendered operable by the timing dial in the operation of the first rotary switching mechanism and an intermittently operated circuit making and breaking mechanism operable by the timing dial, said circuit making and breaking mechanism being connected in a circuit with the second rotary switching means and the means for advancing the rotary switching mechanisms to automatically advance both 10 of the rotary switching mechanisms in a single revolution of the timing dial a number of steps in addition to the number of steps thereof actuated by the motor driven timing dial, said additional steps plus the first-mentioned steps there- 15 of being equal to the number of steps required for a complete revolution of the first-mentioned rotary switching mechanism.

10. In a traffic signal controller of the type

described, the combination as defined in claim 9 wherein said first-mentioned rotary switching mechanism requires eighteen step by step movements thereof to complete one revolution.
